ABSTRACT

A resistive element has a gradient of resistivity extending along its length. It is held in sliding contact with two brushes spaced-apart from each other. The resistance between the brushes can be varied by changing their position relative to the resistive element and the gradient of resistivity. The resistive element may have an arcuate configuration and the relative position may be changed by rotating the element.

VARIABLE RESISTOR

BACKGROUND OF THE INVENTION

This invention relates to a variable resistor for use in electrical circuits and, more specifically, to a variable resistor including a film of resistive material having a gradient of resistivity in a predetermined direction.

In a conventional variable resistor, terminals are provided at the ends of the resistive film and a brush is held in slidable contact with the film to provide a variable resistance between one of the terminals and the brush. The resistance then depends on the position of the brush with respect to the film.

One of the shortcomings of this type of variable resistor is that the inductance component appearing in parallel with the variable resistance undergoes a considerable change depending on the resistance selected. A principal object of the present invention is therefore to provide a variable resistor capable of resistance variation without causing a change in inductance component.

SUMMARY OF THE INVENTION

The variable resistor of the present invention comprises a resistive element having a gradient of resistivity that varies in a predetermined manner along its length and at least two brushes separated by a predetermined interval and held in slidable contact between the resistive element. The desired gradient of resistivity can be given to the resistive element by tapering its width or gradually changing its composition. More than two slidable brushes may be used as required. When more than two brushes are used, a different variable resistance can be across every two every two brushes. The brushes so interconnected so that the distance between them remains constant.

In the variable resistor of this invention, a desired variable resistance is provided between the slidable brushes, while maintaining the accompanying inductance component at a fixed value.

Another feature of the present invention is that the variable resistance never takes the value zero ohms. This contributes to the simplification of a circuit including a finite minimum resistance.

BRIEF DESCRIPTION OF THE DRAWINGS

The present invention will now be described with reference to the accompanying drawings, in which:

FIGS. 1(a) and (b) show equivalent circuits of a conventional variable resistor for the direct-current and extremely low frequency region and for the high frequency region, respectively;

FIGS. 2(a) and (b) show equivalent circuits of an embodiment of the invention for the direct-current and low frequency region and for the high frequency region, respectively;

FIG. 3 is a cross-sectional view of a first embodiment of the invention;

FIG. 4 shows a circuit diagram of a bridged-T type variable resistance attenuator to which this invention is applicable;

FIG. 5 shows a cross-sectional view of a second embodiment of this invention adapted to the attenuator of FIG. 4;

FIG. 6 is an equivalent circuit of a third embodiment of the invention;

FIG. 7 is an equivalent circuit of a fourth embodiment of the invention;

FIG. 8 shows diagrammatically, the impedance variation characteristics of the invention as compared to those of a conventional variable resistor; and

FIG. 9 shows diagrammatically, the frequency characteristics of the conventional bridged-T type variable attenuator and those of the attenuator of FIG. 4 in comparison with the second embodiment of the invention 10 shown in FIG. 5.

DESCRIPTION OF THE PREFERRED EMBODIMENTS

FIG. 1(a) shows an equivalent circuit for a conventional variable resistor comprising a resistive film 10 having terminals 1 and 3 at its ends, and a slidable brush 2 operating in the low frequency range. The desired variable resistance is obtained between the brush 2 and the terminal 3. The resistive film 10 has a uniform specific resistance, and its inductance component is proportional to the length, but negligibly small when a direct current or extremely low frequency signal is applied. Likewise, the capacitive component is also negligible. Generally, the impedance Z_1 between the terminals 1 and the brush 2 is given by:

$$Z_1 = xR + j w x L \quad 1$$

$$|Z_1| = x \sqrt{R^2 + w^2 L^2} \quad 2$$

where R stands for the resistance per unit length of the resistive film 10; L , for the inductance per unit length of the film 10; x , for the length of the section of the film 10 lying between the terminal 1 and the brush 2; and w , for the angular frequency. Differentiating Eq. (2) with respect to x and w ,

$$d|Z_1|/dx = \sqrt{R^2 + w^2 L^2} \quad 3$$

$$d|Z_1|/dw = wL^2 x / \sqrt{R^2 + w^2 L^2} \quad 4$$

From Eqs. (3) and (4), it is apparent that $|Z_1|$ increases linearly with each successive increment of the length x , and non-linearly with each successive increment of the angular frequency w .

The impedance Z_0 of an ideal variable resistor having neither a capacitance component nor an inductance component may be expressed as follows:

$$Z_0 = |Z_0| = xR \quad 5$$

where resistive film is assumed to have a uniform specific resistance R . The ratio A_1 of $|Z_0|$ to $|Z_1|$ is given by:

$$A_1 = \frac{|Z_1|}{|Z_0|} = \frac{x \sqrt{R^2 + w^2 L^2}}{xR} = \sqrt{1 + \frac{w^2 L^2}{R^2}} \geq 1 \quad 6$$

More specifically, the absolute value of impedance is always larger in the conventional variable resistor than in the ideal variable resistor. Also, the larger the angular frequency w , or the smaller the specific resistance R of the resistive film, the greater the ratio A_1 of Eq. (6) becomes. In other words, with the increase of the frequency, the impedance has a greater effect on the variable resistance, making the deviation from the ideal variable resistor greater. An equivalent circuit for a conventional variable resistor at high frequency is shown in FIG. 1(b).

In the equivalent circuits of the variable resistor of the invention shown in FIGS. 2(a) and (b) and the slidable brushes 5 and 6 are in contact with a resistive film

30. The film 30 (resistive element) has a nonlinear gradient of resistivity respect respect to its length. Two brushes 5 and 6, spaced by a predetermined a predetermined interval, are held contact slidable contact with the resistive film 30. between interval between the brushes and the nonlinear gradient in the resistivity of the film 30 are that the so that the resistance and the brushes 5 and 6 exhibits an proportion in linear proportion movement the lengthwise movement of will be brushes. It will be apparent, is not that the invention is not limited to this resistive film arrangement. In general, the gradient may change continuously, linearly or nonlinearly. For simplicity in this explanation, it is assumed here gradient, in other in the gradient, in other words, the rate of the change of the resistivity of linear film 30, is in linear proportion its length. the position selected along its length.

Assuming that the distance from the lefthand end of the resistive film 30 to the brush 6 is x , the resistance therebetween is xR , and the spatial interval between the brushes 5 and 6 is unity, then the impedance Z_2 between the brushes 5 and 6 can be expressed as:

$$Z_2 = x R + j w L \quad (7)$$

$$|Z_2| = x \sqrt{R^2 + (w^2 L^2 / x^2)} \quad (8)$$

where $x \geq 1$ and the variables are the same as those in Eqs. (1) and (2). The ratio A_2 of the impedance $|Z_2|$ of the present variable resistor to the impedance $|Z_0|$ of the ideal variable resistor is given by:

$$A_2 = Z_2 / Z_0 = \sqrt{1 + (wL/xR)^2} \quad (9)$$

where $x \geq 1$.

As in the case of Eq. (6), Eq. (9) indicates that the impedance of the present variable resistor is always larger than that of the ideal variable resistor, and that the value of A_2 is increased with the increase in the angular frequency w . Also, as the resistance xR is increased, the present variable resistor approaches to the ideal variable resistor in its characteristics.

Derived from Eqs. (2) and (3), the ratio A_3 of the absolute value of the impedance of the present variable resistor to that of the conventional one is given by:

$$A_3 = |Z_1| / |Z_2| = (x \sqrt{R^2 + w^2 L^2}) / (x \sqrt{R^2 + w^2 L^2 / x^2}) = \sqrt{(1 + w^2 L^2 / R^2) / (1 + w^2 L^2 / x^2 R^2)} \quad (10)$$

It follows that

$$A_3 \geq 1.0 \quad (11)$$

where $x \geq 1$.

In other words, in the range of $x \geq 1.0$, the variable impedance Z_2 of the present variable resistor is smaller than that Z_1 of the conventional resistor and closer to that of the ideal resistor. FIG. 8 shows the value of A_3 given in Eq. (10) with respect to the length x .

In such a variable resistor, the resistance obtained across the brushes 5 and 6 cannot take the value zero ohms even under the state of unity thus maintaining a certain minimum resistance value. The variable resistor of this invention is therefore highly desirable for those circuits which require a minimum constant resistance.

Referring now to FIG. 3, the first embodiment of the invention, an equivalent circuit of which is shown in FIG. 2, two brushes 106 and 107 are attached to a cylindrical housing 105 and held in contact with an arcuate resistive film 102 attached to a disc-shaped base 103. The film 102 may form a complete circle. The re-

sistive film 102 has a nonlinear gradient of resistivity in the circumferential direction. This gradient is attained by tapering the thickness or the width of the film 102. Alternatively, it may be attained by varying the composition of the material of which the film is made. By the expression gradient of resistivity it is meant that the resistance per unit length of the film varies in a predetermined manner as as it is measured at different points along its length. The base 103 is pressed downwardly by a spring 104 thus permitting rotation under the control of a rotatable disc 101. The desired variable resistance value is thus obtained between the brushes 106 and 107, by changing the relative position of the brushes and the film 102.

Referring now to FIG. 4, a bridged-T type variable attenuator to which the present invention is applied permits a variation in the attenuation depending on the resistance of resistors R_s and R_p which is selected. When conventional variable resistors are used in this attenuator, the voltage standing wave ratio (VSWR) is unavoidably increased with an increase in the frequency. This tends to cause an increase in the impedance Z_1 .

Referring now to FIG. 5, a second embodiment is shown which is adapted to the variable attenuator of FIG. 4 and has a dual variable resistor which may be viewed as two separate variable resistors. Each of these variable resistors is the equivalent to one resistor of the circuit shown in FIG. 2. The dual variable resistor has two brushes 116 and 117 fixed to a base 119 which also serves as a cover. Two arcuate resistive films 112 and 112' having nonlinear resistivity gradients are attached to bases 113 and 114 and kept in slidable contact with the brushes 116 and 117. The resistive films 112 and 112' are moved as a disc 101 on which the bases 113 and 114 are mounted is rotated. These elements are contained in a cylindrical housing 105 and a closure including a base 119. A pair of brushes are provided for each of the resistive films 112 and 112'.

With the dual variable resistor of FIG. 5 used as the resistors R_s and R_p of the bridged-T variable attenuator variable attenuator of FIG. 4, the impedances of the resistors R_s and R_p exhibit virtually no change in the inductive components, as indicated by Eq. (7). Therefore, the voltage standing wave ratio (VSWR) can be kept unchanged as shown in FIG. 9, which illustrates two groups of curves showing the attenuation vs. frequency and the voltage standing wave ratio (VSWR) vs. frequency characteristics of the present variable attenuator as those with those of variable-resistor-based attenuator. variable-resistor-based attenuator.

In the bridged-T type type variable attenuator of FIG. 4, resistances r_s and r_p of the resistors R_s and R_p can be expressed as a function of value attenuation value R_o as follows:

$$r_s = R_o(e^a - 1) \quad r_p = R_o(e^a - 1)^{-1} \quad (12)$$

Where a is given in neper.

The zero attenuation value is achieved by making the resistance r_s and r_p zero and infinity, respectively. Conversely, infinite attenuation achieved achieved by making r_s and r_p infinity and zero, respectively. Practically, however, these requirements cannot be met, infinite impedance impedance is difficult to achieve with a conventional variable resistor. This results in a residual attenuation which causes a high voltage standing wave ratio. Therefore, to achieve a satisfactorily low voltage

standing wave ratio with the conventional device, at least one resistor must be in series with either R_s or R_p or both. In contrast, the variable resistor of the invention never takes the value zero ohms. This makes it possible to dispense with any additional resistance elements and consequently to simplify miniaturize miniaturize the attenuator as a whole. This applies to any apparatus or device in which the present invention finds application.

Referring now to FIG. 6, a third embodiment of this invention has four brushes 202, 203, 204, and 205 spaced at predetermined intervals and held in slidable contact with a resistive film 201. This variable resistor makes it possible to obtain two desired variable resistance values from one resistive film 201, one from the brushes 202 and 203 and the other from the brushes 204 and 205. In other words, a dual variable resistor can be constructed using one resistive film 201. Brushes 203 and 204 may be connected to each other when these two brushes are to be at an equal potential. It will be apparent that more than four brushes can be used.

Referring now to FIG. 7, the fourth embodiment of the invention includes a resistive film 301 having terminals 304 and 305 at the ends, respectively, and brushes 302 and 303 held in slidable contact with the resistive film 301. With a voltage applied between the terminals 304 and 305, the desired voltage is derived from the brushes 302 and 303. In this variable resistor, the inductive component of the output impedance impedance is small and constant. Therefore, the use of this variable resistor in a high frequency device will contribute substantially to better performance.

In the foregoing description, we have explained the

present invention with reference to several exemplary embodiments and their application. However it will be apparent to those skilled in the art that other modifications are possible without departing from the spirit and scope of the invention.

We claim:

1. A variable resistor comprising an electrically resistive element the resistance of which changes along its length in a predetermined manner to form a gradient of

10 resistivity, and at least two spaced-apart movable brushes connected to each other so that the distance between them is fixed and in slidable contact with the resistive element, whereby the resistance obtained between the brushes can be selected by positioning the brushes relative to the resistive element and the gradient of resistivity but the inductance between the brushes remains substantially constant regardless of the position selected.

15 2. A variable resistor set forth in claim 1, wherein said brushes and said resistive element are supported by a housing whereby said brushes are held against said resistive element.

20 3. The variable resistor set forth in claim 1, further comprising a disc-shaped member to which said resistive element is attached.

25 4. The variable resistor set forth in claim 3, further comprising a housing by which said disc-shaped member is rotatably supported.

30 5. The variable resistor of claim 1, further comprising a cylindrical housing and a disc-shaped member rotatably supported within the housing, the resistive element having an arcuate configuration and being attached to the disc-shaped member for rotation therewith.
